CLAIM

The ornamental design for a bottle containing wooden ball, as shown and described.

DESCRIPTION

FIG. 1 is a front and bottom perspective view of a first embodiment of a bottle containing wooden ball, showing our new design;

FIG. 2 is a front view thereof, with the rear view being a mirror image thereof;

FIG. 3 is a right side view thereof;

FIG. 4 is a top view thereof;

FIG. 5 is a bottom view thereof;

FIG. 6 is a front and bottom perspective view of a second embodiment of a bottle containing wooden ball, showing another embodiment of our new design;

FIG. 7 is a front view thereof, with the rear view being a mirror image thereof;

FIG. 8 is a right side view thereof;

FIG. 9 is a top view thereof; and,

FIG. 10 is a bottom view thereof.

The features shown in broken lines depict portions of the bottle containing wooden ball, and environmental structure in the form of an additional wooden ball, that form no part of the claimed design. The dash-dot horizontal line across the middle of the bottle in FIGS. 1-3 and 6-8 illustrates the boundary of the claimed design and forms no part of the claimed design itself. The wood grain surface shading on the ball is provided only to illustrate that the ball itself is wooden; the actual texture and configuration represented by the shading form no part of the claimed design.
